UNITED STATES PATENT OFFICE.

WILLIAM R. KALES, OF DETROIT, MICHIGAN.

WRIST-WATCH BRACELET.

1,216,322.

Specification of Letters Patent. Patented Feb. 20, 1917.

Application filed April 7, 1916. Serial No. 89,586.

To all whom it may concern:

Be it known that I, WILLIAM R. KALES, a citizen of the United States of America, residing at Detroit, in the county of Wayne 5 and State of Michigan, have invented certain new and useful Improvements in Wrist-Watch Bracelets, of which the following is a specification, reference being had therein to the accompanying drawings.

10 The invention relates to bracelets designed for the carrying of a watch upon the wrist, and it is the object of the invention to obtain a simple construction which may be more easily secured in position.

15 In the present state of the art it is usual to provide a pair of straps which are attached to opposite sides of the watch, one being provided with a buckle for the engagement of the other. In applying the watch 20 to the wrist the strap must be disengaged from the buckle, and the reengagement is difficult, as the operator has only one hand free for use. It is usually impossible to slip the bracelet over the hand without disengaging the strap from the buckle, as a long 25 strap is objectionable in appearance.

With my improved construction instead of having two straps secured to the opposite sides of the watch, one carrying the buckle, 30 I use a single strap having a buckle at one end and of sufficient length to pass around the wrist to the opposite side of the watch and to return again for engagement with the buckle. On account of the returning of the 35 strap it may be of sufficient length to remain in engagement with the loop on the watch, providing slack sufficient for slipping over the hand of the wearer. The strap may then be drawn up, which will clamp the watch 40 to the wrist, and when thus secured the engagement of the end of the strap to the buckle becomes a simple operation.

In the drawings:

Figure 1 is a perspective view of a watch 45 and bracelet, showing the strap loose and ready for engagement over the hand of the wearer;

Fig. 2 is an elevation illustrating the watch in position upon the wrist with the 50 strap drawn taut but before buckling; and

Fig. 3 is a similar view with the strap buckled and secured.

In detail, A is a watch which is provided with rings or loops B and B' upon opposite

sides thereof. C is a strap having a buckle 55 D at one end thereof and of sufficient length to pass from one loop around the wrist to the other and to return again for engagement with the buckle. Adjacent the buckle there is provided a keeper D' through which the 60 strap is passed to form a securing loop.

In applying to the wrist the strap is loosened, as shown in Fig. 1, the hand being slipped through the loop, after which the strap is drawn taut, as shown in Fig. 2. It 65 is then returned around the wrist and engaged with the buckle D, as shown in Fig. 3.

What I claim as my invention is:—

1. The combination with a wrist-watch having strap engaging loops or rings upon 70 opposite sides thereof, of a securing strap therefor having a loop adjacent one end engaging one of the rings of said watch, and a keeper maintaining said loop closed and a buckle engaging said end, the length of the 75 strap being sufficient to permit passing the same through the other ring of said watch to form a loop permitting insertion of the hand therethrough and to permit a return-bending of the strap around said loop to engage the buckle. 80

2. The combination with a wrist-watch having strap engaging loops or rings upon opposite sides thereof, of a securing strap therefor having a closed loop adjacent one 85 end thereof for engaging one of the rings of said watch, and a buckle engaging said end, the length of the strap being sufficient to permit passing of the same through the other ring of said watch to form a loop permitting insertion of the hand therethrough and to permit a return-bending of the strap around said loop to engage the buckle. 90

3. The combination with a wrist-watch having strap engaging loops or rings upon 95 opposite sides thereof, of a securing strap therefor having a closed loop adjacent one end thereof for engaging one of the rings of said watch, and a fastening device engaging said end, the length of the strap being 100 sufficient to permit passing through the other ring of said watch to form a loop permitting insertion of the hand therethrough and to permit a return-bending of the strap around said loop to engage said fastening device. 105

In testimony whereof I affix my signature.

WM. R. KALES.
